UNITED STATES PATENT OFFICE.

WILLIAM HARRISON MEARS, OF ELGIN, AND THOMAS A. MEARS, OF SAVANNA,
ILLINOIS.

WIRE-FENCE STRETCHER.

1,074,278.

Specification of Letters Patent.

Patented Sept. 30, 1913.

Application filed February 2, 1912. Serial No. 675,087.

To all whom it may concern:

Be it known that we, WILLIAM H. MEARS and THOMAS A. MEARS, citizens of the United States, residing at Elgin and Savanna, respectively, in the counties of Kane and Carroll, respectively, and State of Illinois, have invented certain new and useful Improvements in Wire-Fence Stretchers; and we do hereby declare the following to be a full, clear, and exact description of the invention, such as will enable others skilled in the art to which it appertains to make and use the same.

Our invention relates to certain new and useful improvements in devices for stretching barbed wire and woven wire fences and has for its object to provide a simple and economically constructed device embodying not only means for stretching the wire but auxiliary means for holding the wire in its stretched condition while the same is being secured to the supporting posts.

With these ends in view our invention consists in the details of construction hereinafter more specifically described.

In order that those skilled in the art to which our invention appertains may know how to make and use the same and fully appreciate its many advantages, we will proceed to describe the construction and operation of the same.

In the accompanying drawing Figure 1 represents a perspective view of our improved device as applied to the woven wire fence and post, both of which are shown in broken lines; and Fig. 2 is a perspective view illustrating the form of hooks employed in connection with the device.

Similar reference numerals indicate like parts in both figures of the drawing.

1. represents a suitable handle or lever of any suitable material, preferably wood, having the proper degree of strength to which is secured on one side a post embracer 2, which may be made of cast metal but which is preferably bent into form from sheet metal of suitable gage and strength to resist the ordinary strain which may be exerted upon it. The embracer shown in the drawing is formed from a single strip of metal by bending the same laterally then back on itself to form the lug projections 2'. The end portions 3 of the embracer are in alinement with the central portion thereof, 55 rest flatly against the lever 1, and are se-

cured thereto by means of the eye bolts 4. To the eye bolts 4 are secured chains 5. and 6. carrying at their outer ends hooks 7., the preferred form of which is most clearly shown at Fig. 2.

In using our improved stretcher, the embracer 2 is placed against the rear surface of the post 8. and the hook 7. on the chain 5. at the end of the handle or lever is placed around the horizontal wire and behind the vertical wire, as shown at Fig. 1., or if barbed wire is to be operated upon, the hook is placed behind a barb. When thus adjusted, the outer end of the handle or lever 1. is drawn toward the operator and consequently strain is exerted upon the outer chain 5. and the wire around which the hook 7. is located is drawn naturally toward the post to such extent as may be desired, whereupon the hook 7. at the end of the chain 6. is placed around the wire or barb in rear of the locality of the hook upon the chain 5. When this has been done it will be readily seen that the stretching device is held in fixed relation with the post even though the handle or lever be released, and consequently the operator is free to employ his hands in stapling the wire or fence to the post. The embracer 2 comprises a slidable or rotatable fulcrum. As the tension on the wire is increased, the weight arm is proportionally shortened, owing to its angular displacement, and it will be apparent that, as the power arm comes nearly into alinement with the wire, the length of the weight arm will be greatly decreased. This structure reduces the liability of breaking the weight arm of the lever at the fulcrum. In the initial movement, the handle operates as a lever of the first class, and in its reverse movement, as a lever of the third class. As such a lever, its efficiency is somewhat reduced, but the embracer sliding about the post gives the lever increasing power as the pull advances.

While we have preferred hooks of the design shown it will be understood that we do not wish to be limited in this respect, as we may employ hooks of any design which may be especially adapted to the uses to which they may be put.

While chains 5. and 6. which carry the hooks may be of equal length in which case the hook upon chain 7. would naturally be located at a point more distant than the

hook upon chain 5., while as a matter of convenience it may be preferred to have the chain 6. somewhat shorter than the chain 5., in which case when the hook 7. of said chain is secured in position upon the wire it will occupy the relative relation to the hook upon chain 5., as illustrated in the drawing.

Many changes may be made in the details of construction and the use of material without departing from the spirit of our invention which involves the generic feature of a lever or handle provided at its outer end with a post embracing device with chains connected to said device and handle or lever at opposite terminals of the said embracing device and provided at their free ends with hooks adapted to interlock with a barbed wire or woven wire fence in order that when the wire or fence has been stretched by the strain exerted upon the chain and hook at the outer end of the lever or handle, the hook at the outer end of the chain 6. may be connected with the wire or fence to hold the latter in its stretched condition, even though the handle or lever may be released by the operator in order that he may have free use of the hands in stapling the wire or fence to the post.

From the description of the construction and the operation thus given it will be seen

that the device is exceedingly simple in construction and may, therefore, be most economically produced and that the several parts when become worn or broken under adverse conditions, may be readily replaced.

Describing the construction, operation and advantages of our improved stretcher what we claim as new and desire to secure by Letters Patent is,

A wire stretcher of the character described, comprising a lever, an embracer secured longitudinally thereto adjacent one end, said embracer being formed from a single strip of metal and having a pair of laterally extending portions formed intermediate its ends, the opposed sides of said portions and that part of the embracer which lies between said portions being adapted for engagement with a fence post, the ends of the embracer being in alinement with the central portion thereof, means for securing said embracer to the lever, and wire engaging members secured to said means.

In testimony whereof we affix our signatures in presence of two witnesses.

WILLIAM HARRISON MEARS.
